UNITED STATES PATENT OFFICE.

RICHARD WEBB BURNETT, OF MONTREAL, QUEBEC, CANADA.

CAR-ROOF.

1,194,709.

Specification of Letters Patent. Patented Aug. 15, 1916.

Application filed November 22, 1911. Serial No. 661,837.

To all whom it may concern:

Be it known that I, RICHARD WEBB BURNETT, residing at the city of Montreal, Province of Quebec, Dominion of Canada, have 5 invented certain new and useful Improvements in Car-Roofs; and I do hereby declare that the following is a full, clear, and exact description thereof.

The object of my invention is to provide a 10 car roof all strains between the principal members whereof are converted into shearing action at the points of union, and to this end the invention consists of metallic purlins and metallic carlines of angular cross-section with their flat sides in contact and 15 rigidly connected together thus forming an homogeneous roof frame.

The invention further consists of the construction, combination and particular arrangement of parts hereinafter described and pointed out in the claims. For full comprehension, however, of my invention reference must be had to the accompanying drawings forming a part of this specification 25 in which similar reference characters indicate the same parts, and wherein:

Figure 1 is a part plan view and part horizontal sectional view of a car roof containing my invention taken on line A A Fig. 30 2; Fig. 2 is a transverse vertical sectional view taken on line B B Fig. 1; Fig. 3 is a part side elevation and part longitudinal sectional view taken on line C C Fig. 1; and Fig. 4 is an enlarged detail sectional view 35 taken on line D D Fig. 1.

The sides 2 2 and ends 3 of the car may be of any preferred construction with Z-iron side plates 4 and angle-iron end plates 5.

According to my invention the roof frame 40 consists of a series of arched carlines 6 of channel-iron and a series of inverted channel-iron purlins 7 arranged back-to-back and rigidly connected by electric welding. The ends 45 of the purlins rest upon and are riveted to the end plates 5 as at 8 and the carlines have the ends of their flanges cut off and the portions contiguous to the ends sheared off as at 9, the ends 10 of the webs being bent 45 down over the side plates and riveted there-

to as at 12. This homogeneous frame carries the roof sheets which consist of corrugated metal, the sides of the sheets being bent over the flanges of the carlines as at 13 with their edges turned up as at 14 to 55 afford means of attachment permitting maximum play of the sheets without wearing upon the edges of the carlines. This attachment means comprises a series of studs 15 welded to the carlines and threaded to receive nuts 16, the turned up edges 14 being borne upon by the edges of curved plates 17 through which the studs project, such plates being clamped in place by the nuts 16, thus affording the freedom of play for the sheets 60 as above mentioned.

The running board 20 is carried on Z-brackets 21 electrically welded to the bottom webs of the carlines. This construction has the advantage of direct connection between the carlines and purlins and between the running-board brackets and the carlines and with electrically soldered joints that all strains upon these members are converted 70 into shearing action at the point of union 75 which is rendered of maximum strength by the electrically welded joint.

What I claim is as follows:—

1. In a car the combination with the roof-frame containing a series of channel-iron 80 carlines, of a series of roof-sheets having downwardly bent side edges of sufficiently greater width than the flanges of the carlines to provide clearance spaces therebetween, and means securing the extremities 85 alone of the said side edges to the interior of the webs of the carlines.

2. In a car roof, a metallic carline of channel cross-section arranged with its flanged portions extending upwardly, a securing member welded to the top of the web portion of said carline, roof sheets having downwardly-bent edge portions extending between the flanges and upwardly-bent extreme edge portions adjacent the web portion of said carline, a clamping plate for engaging the edge portions of the roof sheets, and means for securing said clamping plate to said securing member.

3. In a car roof the combination with a 100

roof-frame having a series of upwardly turned channel-iron carlines, of roof-sheets with downwardly turned side edges entering the carlines and having turned-back extreme edges, and means fastening the turned back edge-portions to the interior of the carlines.

In testimony whereof I have signed my name to this specification in the presence of two witnesses.

RICHARD WEBB BURNETT.
